United States Patent Office

Des. 181,185
Patented Oct. 15, 1957

181,185

SLIDE PROJECTOR

Harry J. Collins, Milwaukee, Wis., assignor to David White Instrument Company, Milwaukee, Wis., a corporation of Wisconsin

Application March 18, 1957, Serial No. 45,289

Term of patent 14 years

(Cl. D61—1)

Fig. 1

Fig. 2

FIG. 3

FIG. 4

Fig. 1 is a front elevational view of a slide projector, showing my new design;

Fig. 2 is a side elevational view;

Fig. 3 is a top plan view; and

Fig. 4 is an opposite side elevational view thereof.

A portion of drawing Fig. 1 is diagonally lined to indicate transparency.

I claim:

The ornamental design for a slide projector, as shown and described.
